UNITED STATES PATENT OFFICE.

HALVER R. STRAIGHT, OF ADEL, IOWA.

KILN CAR.

Application filed October 7, 1926. Serial No. 149,100.

This invention relates to kiln cars of that type which is used in continuous kilns, and of that type having a floor, for supporting the ware, constructed of a series of hollow blocks 5 formed of fire clay or other heat resisting material.

Considerable difficulty has been experienced with cars of this type due to the expansion and contraction of that portion of the car frame which is designed to support the floor blocks in position.

It is, therefore, the object of my invention to provide an improved kiln car of simple, durable and inexpensive construction which 15 is provided with a retainer frame, for securing the blocks in position on the car, supported in movable relation with the car frame so that the said retainer frame may be moved independently thereof to provide for 20 the difference in expansion between the said retainer frame and the car frame. The retainer frame is provided with means whereby it will be supported in fixed relation with 25 said car frame when the maximum amount of expansion has taken place.

A further object is to provide in a kiln car of the type above described, an improved floor construction.

A further object is to provide in a kiln car 30 having a retainer frame for supporting the floor blocks in position improved means whereby the upper edge of said retainer frame may be shielded from the intense heat.

My invention consists in the construction, 35 arrangement and combination of the various parts of the device, whereby the objects contemplated are attained, as hereinafter more fully set forth, pointed out in my claims, and illustrated in the accompanying drawings, in which:

Figure 1 is a plan view of my improved car.

Figure 2 is a side elevation of one end of said car.

Figure 3 is a detail end elevation of a portion 45 of one end of said car.

Figure 4 is an enlarged, detail, sectional view taken on the line 4—4 of Figure 1.

Figure 5 is an enlarged, detail, sectional view taken on the line 5—5 of Figure 1.

Figure 6 is an enlarged, detail, sectional view taken on the line 6—6 of Figure 1.

Figure 7 is an enlarged, detail, sectional view taken on the line 7—7 of Figure 1.

Figure 8 is a detail sectional view taken on 55 the line 8—8 of Figure 6.

My improved device comprises a car frame

having longitudinally extending angle irons 10. Said angle irons 10 are spaced apart and secured to a channel iron 11, said members 10 and 11 forming the side members of the 60 frame. Said side members are spaced apart and secured together by means of transversely arranged frame members 12, each of which has its upper surface provided with an inverted T-iron 13, as shown in Figures 6 65 and 7. The angles 10 are also spaced apart by means of sleeves 14 to receive tie bolts 15. The lower edges of the downwardly extending flanges of the members 10 are provided with notches 16. Each pair of notches 16 is 70 designed to receive an axle 17 for supporting the car wheels 18, said axles being secured in position by means of angle bolts 19, in the manner clearly illustrated in Figure 4. The members 10, 11, 12 and 13 form what I shall 75 term the car frame.

The T-irons 13 and the inner edges of the frame members 10 are designed to support corrugated plates 20 which serve as means for supporting a floor hereinafter described. 80 The said plates are corrugated to permit expansion and contraction without warping, and also for the purpose of stiffening the plates.

Supported on the car frame is what I shall 85 term a retainer frame for the purpose of supporting the floor blocks, hereinafter described, in position on the car. Said retainer frame comprising two longitudinally extending frame members 21, each of which is preferably formed of cast metal having a horizontal portion 22 which lies substantially in the same plane as the upper flanges of the angles 10. The inner edges of the members 22 are provided with ribs 23 overlapping the 90 outer edge of the adjacent angle member 10, so that lateral movement of the member 22 is permitted relative to the member 10. The outer edge of the member 22 is provided with an upwardly extending portion 24 terminating at its upper end in a horizontal portion 25, which in turn terminates in an upwardly extending flange 26. The flange 26 is provided with a series of notches 27, so that the flange 26 may be permitted to expand 95 and contract to a greater extent than the member 24, without buckling or warping.

Suitable transversely arranged ribs 28 are provided for bracing the members 22, 24 and 25 relative to each other. The corresponding 100 ends of the members 22 and 24 are joined together by means of transversely arranged 105

ends of the members 22 and 24 are joined together by means of transversely arranged 110

angle irons 29, having their flanges arranged vertically and horizontally. The horizontal flanges are movably supported by the outer ends of the members 10 and 11.

6 By this arrangement it will be seen that the side members of the retainer frame are free to move laterally relative to the member 10. The entire frame is held against longitudinal movement relative to the car frame by means 10 of a bar 30 secured to the central portion of one of the members 29, by means of suitable bolts 31, said bar extending inwardly and having its inner end secured to one of the cross bars 12.

15 Secured to the inner face of each of the members 24 I have provided inwardly extending tie bars 32 slidably supported on the upper faces of the angles 10 and the channels 11. The inner end of each of the bars 20 32 is provided with a hook 33 for surrounding the inner edge of each of the inner angles 10. Said bar 32 is of such length that when the car is cold and the retainer frame is normally supported thereon, a space 34 will 25 be provided between the inner edge of the angle 10 and the hook portion 33. The horizontal width of this space is equal to one-half the total amount of the lateral expansion of the retainer frame, so that when the maximum amount of the expansion has taken 30 place, the hook 33 will engage the inner edge of the angle iron 10. The hook 33 is also provided with a portion 35 which serves to prevent the inner ends of the tie bar 32 from 35 being elevated, thereby providing means for preventing twisting of the bars 22 and 24 due to the load carried by the flange 26.

The lower edge of each of the members 24 is provided with downwardly extending 40 shield plates 36 for the purpose of entering the sand seals of the ordinary construction. It will be seen that the flange 26 overhangs the upper edge of the shield 36 a considerable extent, and for that reason protects the said 45 shield against a large percent of the downward radiation of heat from the flange 26 and the outer ends of the floor blocks, hereinafter described.

The top portion of the angles 10 and the 50 channel 11, together with the flange 22 are covered with a loose heat insulating material 37, such as ashes or sand, said insulating material being of a depth equal to the height of the rib 23 and the corrugated plate 20. The 55 insulating material 37 and the plate 20 is then covered with a layer of heat insulating material 38 which may be placed thereon in plastic condition and permitted to dry, or it may be in the form of bricks laid in heat 60 resisting cement. The top of the insulating floor 38 is substantially level with the top edges of the flanges 26. A groove 39 is provided at each side of the floor 38 of a depth equal to the depth of the flange 26. The 65 grooves 39 are designed to receive a series of

floor blocks 40 formed of insulating and fire proof material. The under surface of the outer end of each of the blocks is provided with a groove 41 for receiving the upper edge of the flange 26 in such a manner that a portion of the outer ends of the blocks 40 overhang the said flange. The overhanging ends provide means for protecting the flange 26 against the intense heat. The notches 41 serve to retain the blocks 40 against movement transversely with the longitudinal movement of the car.

The top edges of the blocks 40 are supported above the upper face of the insulating floor 38 a slight distance, or a distance equal to the thickness of the lower wall 42 of the hollow floor blocks 43, said blocks being arranged with their central openings extending horizontally and transversely of the car to form air passages through said blocks. The bottom member of each of the blocks 43 of the outer rows of blocks have their outer ends cut away to form notches 44 for receiving the blocks 40, in such a manner that a shoulder 45 is formed, designed to rest against the inner edges of the blocks 40. Thus means is provided for anchoring the blocks 43 against outward movement, due to the stacking of the ware on the said blocks. The blocks 40 and 43 are capable of lateral movement relative to the insulating floor block 38, to a certain extent, to permit lateral movement of the flange 26 due to expansion and contraction on account of temperature variations. The loose insulation 37 is provided to permit the member 22 to move laterally relative to the member 10.

By this arrangement it will be seen that the retainer frame 24 may expand and contract relative to the frame members 10 and 11 without materially effecting the gauge of the wheels 18 and also without warping or twisting the main car frame.

It will readily be seen that a considerable difference in temperature will be maintained 110 between the retainer frame and the car frame, due to the fact that the car frame can be quite thoroughly insulated and is usually cooled by the circulation of cold air, while the upper edge of the retainer frame has to be maintained at a high temperature at the time the car is being passed through the burning zones of the kiln.

The tie bars 32 serve to prevent the central portions of the side members of the retainer frame from being bulged outwardly at the time the said frame member is in a heated condition, at which time the resiliency of the metal is greatly reduced. In fact, the resiliency of the members 22, 24 and 26 should be such that when the said members are cooled, they will crowd the blocks 40 and 43 inwardly so that the outer faces of the sides of the stacked ware will be substantially straight. It should be borne in mind that

cars of this type are designed to be passed through tunnel kilns in which the side walls are supported very closely to the side edges of the stack of ware, to prevent an excessive passage of heated air from moving past the stack of ware at certain points of the kiln walls. For that reason it is necessary that the ware be uniformly and symmetrically stacked on the car, and that the said side faces be maintained in a straight and symmetric manner, regardless of whether the ware is cold or heated.

By providing the notches 27 in the members 26, I have provided means whereby the excessive longitudinal expansion of the upper edges of the flange 26 will be prohibited, and thereby prevent warping or buckling of the flange 24, which would otherwise occur.

I claim as my invention:

1. In a device of the class described, a car frame, a floor supported thereon, a retainer frame supported on said floor and capable of horizontal movement relative to said car frame, and a series of floor blocks carried by said floor and within said retainer frame.

2. In a device of the class described, a car frame, a floor supported thereon, a retainer frame, a series of floor blocks within said retainer frame and carried by said floor, said blocks and said frame being capable of a slight outward movement relative to said floor and said car frame to compensate for the difference in expansion between the car frame and said floor blocks.

3. In a device of the class described, a car frame, a floor for said frame, a retainer frame supported on the outer edges of said car frame, capable of slight outward and inward movement relative to said car frame, and means for anchoring one point of said retainer frame in fixed relation to said car frame.

4. In a device of the class described, a car frame, a floor for said frame, a retainer frame supported on the outer edge of said car frame capable of movement relative thereto, the outer edge of said car frame being provided with an outwardly and upwardly extending flange, said flange being provided with a series of transverse notches, for the purposes stated.

5. In a device of the class described, a car frame, a floor for said frame, a retainer frame supported on the outer edge of said car frame capable of movement relative thereto, the outer edge of said car frame being provided with an outwardly and upwardly extending flange, said flange being provided with a series of transverse notches, a series of floor blocks having their outer ends overhanging said upwardly projecting flange, the under surface of the overhanging portion of each of said floor blocks being provided with a groove for receiving said upwardly projecting flange.

6. In a device of the class described, a car

frame, having parallel side and end members and transversely arranged brace members, and a panel floor section formed of corrugated sheet metal between and carried by said brace members.

7. In a device of the class described, a car frame having parallel side and end members and transversely arranged brace members, sheet metal floor sections carried by said transversely arranged braces and side members, a retainer frame movably supported on the outer edge of said car frame, said retainer frame comprising parallel side and end members, means supporting one point of one of the end members in fixed relation with said car frame, and brackets for limiting the outward movement of the side members of said retainer frame relative to the side members of said car frame.

8. In a device of the class described, a car frame having parallel side and end members, a retainer frame movably supported on the outer edge of said car frame, said retainer frame comprising parallel side and end members, and means supporting one point of one of the end members of said movable frame in fixed relation with said car frame.

9. In a device of the class described, a car frame having parallel side and end members, a retainer frame movably supported on the outer edge of said car frame, said retainer frame comprising parallel side and end members, means supporting one point of one of the end members of said movable frame in fixed relation with said car frame, and brackets for limiting the outward movement of the side members of said retainer frame relative to the side members of said car frame.

10. In a device of the class described, a car frame having parallel side and end members, a retainer frame movably supported on the outer edges of said car frame, said retainer frame comprising parallel side and end members, and brackets for limiting the outward movement of the side members of said retainer frame relative to the side members of said car frame.

11. In a device of the class described, a car frame comprising side members and end members, each of said side members comprising a pair of parallel angle irons supported with two of their flanges adjacent and parallel and secured together by a channel iron having its body portion in alignment with the other two flanges of said angles, transversely arranged beams for supporting said side members in fixed and parallel relation with each other, an inverted T-iron for the upper edge of each of said transversely arranged beams, axles detachably secured to the lower edge of said downwardly extending flanges, and a wheel for each of said axles.

12. In a device of the class described, a

car frame comprising side members and end members, each of said side members comprising a pair of parallel angle irons supported with two of their flanges adjacent and parallel and secured together by a channel iron having its body portion in alignment with the other two flanges of said angles, transversely arranged beams for supporting said side members in fixed and parallel relation with each other, an inverted T-iron for the upper edge of each of said transversely arranged beams, axles detachably secured to the lower edge of said downwardly extending flanges, a wheel for each of said axles, and a corrugated sheet metal panel supported by and between two adjacent T-irons and between the inner edges of said angle irons.

13. In a device of the class described, a car frame comprising side members and end members, each of said side members comprising a pair of parallel angle irons supported with two of their flanges adjacent and parallel and secured together by a channel iron having its body portion in alignment with the other two flanges of said angles,

versely arranged beams for supporting said side members in fixed and parallel relation with each other, an inverted T-iron for the upper edge of each of said transversely arranged beams, axles detachably secured to the lower edge of said downwardly extending flanges, a wheel for each of said axles, a corrugated sheet metal panel supported by and between two adjacent T-irons and between the inner edges of said angle irons, and a retainer frame supported on the outer edges of said car frame, said retainer frame being capable of slight lateral movement relative thereto.

14. In a device of the class described, a car frame, a floor supported thereon, a retainer frame supported on said floor and capable of horizontal movement relative to said car frame, a series of floor blocks carried by said floor and within said retainer frame, and means for limiting the relative movement between said retainer frame and said car frame.

Des Moines, Iowa, September 24, 1926.
